ASH TRAY OR THE LIKE

James Babcock, Pomona, Calif., assignor to James Babcock Associates, Inc., Beverly Hills, Calif., a corporation of Nevada

Application November 23, 1954, Serial No. 33,192

Term of patent 3½ years

(Cl. D85—2)

The broken line showing of legible matter is for illustrative purposes only. Portions of the article are diagonally lined to indicate the presence of a transparent protective member.

I claim:

The ornamental design for an ash tray or the like, substantially as shown and described.
